SHELL MAKING

William C. Coryell, Youngstown, Ohio

Application June 15, 1940, Serial No. 340,754

4 Claims. (Cl. 29—1.21)

The present invention relates to shell making and particularly the making of ordnance shell.

It is well known that in the firing of a gun loaded with a shell and an explosive charge, the explosion of the charge produces a stress within the shell which is highest at the base of the shell and gradually less toward the ogive of the shell, as the latter is being expelled from the gun. In consequence of this action it is desirable to have the base of the shell structure particularly strong.

To put it another way, the inertia of the shell is what is to be overcome in discharging the shell from the gun. That inertia is greatest at the base of the shell. As one proceeds from point to point along the shell toward the ogive, the inertia to be overcome gradually decreases. Thus, at any given point along the shell the inertia is that resulting from the portion of the shell between that point and the ogive. Obviously, this becomes less and less as one proceeds toward the ogive.

One object of the present invention is to provide a novel method by which the base of the shell will be strengthened. This is accomplished preferably by a reduction in the diameter of the shell blank accompanied with a twisting of the material, especially near the base.

Another object is to provide a method by which such shell shall be produced without losing any of the advantages and values possessed by shell as made heretofore.

Another object is to provide a method by which the shell may be made with equipment which will require but slight modification of present equipment.

Another object is to provide a novel method which will permit the manufacture of shell economically both in respect to labor and material.

Other objects and advantages of the invention will be apparent from the following description taken in connection with the accompanying drawings, while the scope of the invention will be particularly pointed out in the appended claims.

Referring to said drawings, Fig. 1 is a longitudinal section of a bell-shaped metal blank upon which the steps of the novel method are performed to bring about the finished product, all in accordance with the present invention. Fig. 2 is a similar section of the shell structure after the steps of the method have been performed upon the blank. Fig. 3 is a side elevation of the finished shell upon which is a spiral line indicating the twist which is given to the metal of the shell during the process of manufacture. Fig. 4 is a perspective view on a somewhat smaller scale

of the blank of Fig. 1. Fig. 5 is a perspective view of the finished shell. Fig. 6 is a side elevation of the cross rolls which are employed in carrying out the new method. Fig. 7 is an end view of these rolls with the shell blank in position between them. Fig. 8 is a plan view of the cross rolls also illustrating the shell blank in position between them, the latter, however, being shown in section. Figs. 9 and 10 are horizontal sectional views of the blank at intermediate stages of reduction, the same being shown in each instance with a portion of the cross rolls to indicate the extent of travel of the blank between the rolls. Fig. 11 is an elevation of a cross roll mounted in its roll housing. Fig. 12 is a vertical sectional view illustrating a cross roll in association with its housing and the main housing of the mill, the plane of section being indicated by the line 12—12 of Fig. 14. Fig. 13 is a similar view illustrating certain of the parts in elevation, the plane of section being indicated by the line 13—13 of Fig. 14. Fig. 14 is an elevation of the complete cross roll mill which is preferably employed in performing certain steps of the novel method. Fig. 15 is an end elevation of the same mill. Fig. 16 is a top elevation of the same mill. Fig. 17 is a vertical section through a portion of the mill showing particularly the guides for the blank, the plane of section being indicated by the line 17—17 of Fig. 14. Fig. 18 is a partial end elevation of the guide structure shown in Fig. 17. Fig. 19 is a plan view of the cross roll mill in association with suitable drives and a heating furnace. Fig. 20 is a horizontal section 30 through a portion of the mill illustrating adjusting mechanism, the plane of section being indicated by the line 20—20 of Fig. 14. This method contemplates the rolling and twisting of the shell blank either with or without the use of a mandrel. Fig. 21 is a longitudinal section of a blank A and a mandrel in position for rolling. Fig. 22 is a longitudinal section of the blank after being rolled and twisted and before being removed from the mandrel. Fig. 23 shows a longitudinal section of the blank after the base has been partially closed in and upset. Lastly, Fig. 24 shows a longitudinal section of a blank after the rough machining operations have been completed.

Throughout the views, like characters refer to 45 like parts.

According to the present invention the blank is first heated to a suitable temperature and then worked up by reducing and twisting to provide the finished product, all as herein disclosed.

The equipment for accomplishing these steps

of the novel method is illustrated generally in Fig. 19. As shown there, the blank A after being heated in the furnace B is passed over the guides to the cross roll mill C and emerges from the latter in its final form as the shell blank D. Suitable drives E and F are provided for the cross rolls of the mill.

It should be noted that the blank A may be made in any desired way. It is composed of steel suitable for the manufacture of shell and is preferably bell-mouthed and more or less conical in shape as illustrated.

Obviously, in the production of the blank the extent of opening at the base of the blank may be varied and the length and shape in other respects may be modified, but in general it has the outline of the blank illustrated in Figs. 1 and 21. These are all matters of design dependent upon the characteristics of the shell to be made and the character of the cross roll mill employed in the making of the same. Since the blank is to be passed point-first through the cross roll mill C, it is obvious that any fins, flaws and slight projections found thereon should be removed and the blank otherwise cleaned up so that it will pass readily into and through the mill. In some instances it might be even desirable to cut away a portion of the material to remove these undesirable projections, and to otherwise properly prepare the surfaces.

As indicated, the conical blank A when properly reduced and twisted according to the present invention will result in the shell-blank D. But it will be noted that the shell blank D is still a blank inasmuch as the same will be subjected to further machining inside and outside. In passing from condition of the blank A to the condition of the blank D, the metal near the base is reduced as indicated in Figs. 1 and 2 by the imaginary rings, a, b and c of the blank A, becoming the imaginary rings a¹, b¹ and c¹ of blank D. These imaginary rings in both instances are employed in these figures to illustrate approximately how the metal flows in passing from one form to another. These sets of imaginary rings show equal volumes of material. Thus, the material in ring, a, has the same volume as the ring, a¹. Likewise, the material in ring, b, has the same volume as in ring, b¹. And, again, the volume in ring, c, is the same as in ring, c¹. These imaginary rings thus show approximately the degree of reduction and the distribution of material without taking into account the twist.

When it comes to the twisting which the material receives, there is a different travel and that material which is at one point is transferred, especially at the base, vectorially. This angular shifting of the material is indicated by the spiral line 21 shown on the outside of the shell blank D in Fig. 3. As will appear more fully herein-after when considering the cross rolls, which are preferably employed to provide this lateral shifting of material, the action operates along that portion of the blank in contact with the rolls. Consequently, the unit receiving reduction and twisting at the forward end of the blank receives the least twisting because it is the first to move through the roll pass, and each subsequent unit receives more twist than the preceding units of the blank. This process continues until the last portion of the blank as it passes through the mill has received the greatest amount of twisting and reduction.

It may be noted also that when the shell blank 75

A is to be worked by reduction and twisting so as to be brought into the shape and condition of the blank D, it is worked hot. To give the necessary heat, it is placed in a suitable furnace such as the furnace B (Fig. 19) and when hot it is subjected to the reducing and twisting operations.

It should also be noted that the blank A of Fig. 1 has a boss or projection 24 on its outer surface. This provides an extra thickness of material at the base of the shell. This excess of material is provided in order to furnish that material which will be necessary to the forming of the interior projection 25 upon the shell blank D.

It may also be noted that as the change in the form is made from the blank A to the blank D, there is a slight stretching of the material, so that the blank D is a little longer than the blank A, all of which will be pointed out more fully hereinafter.

While speaking of the shell blank D, it may be well to note that the same comprises a base portion, a body portion, and an ogive portion. The former is at the open end of the shell and is sufficient in extent to include the segmental rings, a¹ and b¹, while the latter is at the closed conical end of the shell and extends generally from about the point 22 to the sharp end, 23, of the blank.

After the blank D is produced and is properly machined within and without, the same will be loaded with its charge of explosive as usual.

Turning now to a consideration of the step of reducing and twisting the blank A to bring it into the form of the blank D, various mechanisms may be employed to permit these functions. Preferably, however, I employ a cross roll mill for this purpose. In such a mill the cross roll will bring about the necessary reduction in diameter and also accomplish the desired twist. Different cross roll mills may be used to this end. However, the same herein illustrated will serve the purpose and accordingly may be described as a generic representation of suitable equipment for giving the required reduction and twist.

In the embodiment illustrated there are two cross rolls R¹ and R². As shown particularly in Fig. 6 their axes are slightly out of parallelism. In other words, they are shifted vertically relative to each other to provide the cross roll action. As shown in Fig. 6 the amount of angularity is exaggerated somewhat to make the drawing clearer in this respect, but in practice it would be in the neighborhood of a few degrees. Obviously, the extent of cross variation may be varied according to the requirements of any given case, the smaller the angularity, the slower the travel of the work through the mill, consequently, the less the work done per revolution of the rolls.

The rolls R¹ and R² are spaced apart a distance such as to properly receive the blank A between them, in the manner illustrated in Fig. 8, where the blank A remains unchanged because it is at the beginning of its entry into the mill pass. As soon as it advances, it will begin to change its shape. The travel of the shell A forward through the pass results from the rotation of the rolls R¹ and R². Each of the latter is provided with an entering conical surface 27, a cylindrical band surface 28 and an outgoing conical surface 29. Each roll is provided with suitable necks 30 and 31. By reason of the conical surface 27 of the rolls, engaging the outer surface of the blank A and by reason of the fur-

ther fact that the axes of the rolls are tilted, the one above the horizontal plane that passes through the axis of the blank being rolled, and the other below that plane, there is produced a combined reduction, twisting and forward movement of the blank. It should be noted that the blank is entered into the pass with the ogive end first. As the blank travels forward through the pass, its conical wall is pressed inwardly toward its longitudinal axis and this operation continues until the blank D is formed, thereby producing a cylindrical body. In Figs. 9 and 10, there are two intermediate positions of the blank shown. These may be designated A¹ and A². Thus the blank enters the mill as blank A and is changed from point to point in shape, passing through the forms of the blanks A¹ and A² and finally reaching the form D.

It should be noted that the rolls R¹ and R² rotate in the same direction. This causes the blank to rotate oppositely as it travels through the pass. In other words, the conical surface 27 has a larger diameter at a point adjacent to the throat of the pass than it has at its entering end. This means that the surface speed of the roll is greater at the throat than at the entering point, but inasmuch as the diameter of the blank is smaller at the throat than at the open end, it follows that the tendency is to rotate the shell faster at the point of the shell than at the base. Disregarding possible surface slippage between the rolls and blank, there results thus an actual twisting of the material composing the body of the blank. This is what is indicated by the line 28 in Fig. 3. As before stated, the degree of twisting may be varied.

It will be noted that as the blank passes through the mill between rolls R¹ and R², it receives no reduction after it passes the conical surface 27. As the shell advances increment by increment, the successive increments are reduced and twisted more and more.

The cylindrical portions 28 of the rolls R¹ and R² perform the function of smoothing the surface of the blank. The surface 29 also performs no work upon the blank, but completes the roll in each instance and provides a better positioning of the bearings for the rolls.

Considering now the mountings for the rolls R¹ and R², each roll has its own housing, thus roll R¹ has its housing 35, and roll R² has its housing 36. Each roll has bearings 37 and 38. These bearings fit into rectangular openings in the end portions of the housings and are held in each instance by a key 39 or other suitable means. As clearly shown, housings 35 and 36 are oppositely positioned and their open sides are toward the space between the rolls R¹ and R². In other words, they are open toward the pass of the mill.

The roll housings 35 and 36 are mounted within the main housing of the mill. The latter includes a base 42 having end uprights 43 and 44. A cap 45 has downward projections 46 which engage the upper ends of the uprights 43 and 44, respectively. Two series of bolts, 47 and 48, provided with suitable nuts serve to secure the cap 45 to the base portion of the housing. The upper portion of the cap 45 is provided with a re-enforcing rib 49, which serves to strengthen the cap and thus enable it to meet the strains placed upon it. The lower base member 42 of the housing is provided with a central pedestal 50, having lateral wings 51. The upper surface of this pedestal serves as a support for one of

the guide members 52 located between the rolls R¹ and R² and is devised to fit the guide 52 and serves to hold it against downward movement as the blank is drawn through the pass of the mill. Cooperating with the lower guide member 52, is an upper guide member 53. The latter is similar in construction to the member 52 but reversed so as to engage the upper portion of this shell-blank and prevent its undue upward movement when being carried through the pass of the mill. The upper guide member 53 is secured to wings 54 located at the lower end of a pedestal 55 which extends downwardly from the housing cap 45.

By reference to Fig. 17, it will be seen that the pedestals 50 and 55 are offset at the inner ends of the guide members 52 and 53, as indicated at 56 and 57. The offset portion 56 provides a face against which the inner end of the guide 52 may abut and be held by suitable T-headed bolts 58. The bolts 58 pass through the pedestal portion 56 and on through openings in a projection 59 located at the forward end of the guide member 52. The T-heads lie forward of the projection 59 and the rear ends of the bolts 58 are provided with suitable nuts. The vertical portion of the pedestal 50 lies beyond the offset portion 56 with respect to the guides 52 and 53, and is cut away as indicated at 60. This is done for the purpose of providing space for the movement of a pivoted table or plate 61, which is in line with the guide 52 and serves to receive the shell blank as it passes out of the mill. This guide 61 may be moved by any suitable mechanism into the full line receiving position and alternately into the dotted line delivering position.

The upper pedestal 55, beyond the offset portion 57, is provided with a lug 62. Through this lug a plurality of bolts 63 are passed. These bolts then extend on through suitable openings in projections 64 and 65 extending upward from the guide member 53. The T-heads of the bolts 63 lie forward of the projection 65 and the rear ends of the same are threaded for the reception of retaining nuts. By screwing up the nuts at the threaded ends of the bolts 58 and 63, the guide members 52 and 53 may be firmly seated and held in place in their guiding position between the rolls R¹ and R².

In the mill which is disclosed, provision is made for adjusting the rolls R¹ and R² toward and from each other. This adjustment is brought about by bodily shifting the housings 35 and 36 of these rolls. Either housing may be moved independently of the other. It will be noted upon inspection that the housings 35 and 36 engage the main housing base 42 and the cap 45 with cylindrical bearings. Thus, as clearly shown in Figs. 12 and 13, the roll housing is provided with cylindrical convex faces 68 and 69. These convex bearing faces fit against concave bearing faces 70 and 71, formed respectively upon the underside of the cap member 45 and upon the upper side of the base member 42. As clearly shown, concave bearing surfaces 70 and 71 are formed upon projecting portions 72 and 73, respectively, of the members 45 and 42. Since these concave and convex abutting surfaces are cylindrical and the axes of the cylinders extend transversely of the roll axis, it is clear that the housings 35 and 36 may be readily moved toward and from each other by a sliding movement lengthwise of the cylinders.

This to and fro movement of the housings 35

and 36 is brought about by independent adjusting mechanisms. These mechanisms include two sets of adjusting screws and connections. That arrangement at the left hand side of the mill, as the parts are viewed in Fig. 14, is clearly shown in Fig. 20. Here a horizontal section discloses the three screws of the set. At the right end of Fig. 14, the vertical arrangement is shown in connection with the other set of adjusting screws. Since the various parts are the same in both sets of mechanisms, it will suffice to describe one set fully and to use the same designating characters upon both sets.

As clearly shown in Fig. 20, there is a central adjusting screw 77 and two outer adjusting screws 78. The screw 77 is provided with a T-head, the screw is passed through a suitable opening in the roll housing 35 and on through a larger opening 79 in the vertical housing 43, leaving the head engaging the inner face of the roll housing. A bridge piece 80 spans the opening 79 and has a hole through it for the reception of the outer end of the threaded adjusting screw 77. A wheel 81 carrying a nut 82, serves to draw upon the screw 77 or release it, all in accordance with the direction of rotation of the wheel. Similarly, the outer screws 78 are provided with hand wheels 83. These hand wheels, however, are secured to the outer ends of the screws 78 so as to rotate them. The threaded portions of the screws 78 cooperate with sleeves 84, mounted in suitable openings in the housing member 43. These sleeves 84 are threaded internally and their threads cooperate with the threads on the screws 78.

When it is desired to shift the housing 35, it is necessary to operate the hand wheels 81 and 83. If the movement of the roll housing 35 is to be toward the main housing member 43, then the hand wheels 83 are operated to draw the screws 78 back from engagement with the housing 35. Following this, the hand wheel 81 is operated to draw the housing 35 toward the member 43. When the desired position is obtained, then the screws 78 are screwed down so as to again press firmly against the housing 35. Obviously, when the reverse movement is required, the central screw 77 is first released and then the other screws 78 are screwed down to force the housing 35 outwardly away from the housing member 43.

Obviously by loosening up the cap 45 from the lower main housing members, the pressure upon the cylindrical bearings 68-70 and 69-71, previously mentioned, will be reduced. It is, therefore, desirable to loosen up the nuts of bolts 47 and 48 when making adjustments. After the adjustment has been completed, then the nuts can be screwed home again. This will place the apparatus in condition for operation.

Coming now to a consideration of the vertical adjustments of the rolls R¹ and R², I have provided mechanisms for rotating the roll housings vertically. In such case the concave and convex cooperating bearing surfaces 68-70 and 69-71 on the housings, slide over each other, not in the direction of the axis of the cylinders, but in a rotative direction at right angles thereto. In this case, as before, it is desirable to loosen up the cap nuts and thus relieve the pressure which exists at these concave and convex bearing surfaces. The mechanisms for bringing about the vertical adjustment of the two roll housings are the same, except that the positions of the screw-operating hand wheels are reversed. Because of this simplicity, it will suffice to explain the parts

which cooperate in the adjustment of one of the roll housings and refer to the reversed arrangement only as becomes necessary. The same reference characters may be applied to both sets of adjusting devices.

If we direct our attention to the vertical adjustment of the roll housing 35, shown at the left of the Fig. 14, then we see that there is an upper adjusting screw 86, and a lower adjusting screw 87. As clearly shown in Figure 12, the upper adjusting screw is provided with a lower threaded portion, the threads of which engage with the inner thread of a sleeve 88, which is suitably mounted in an opening of the cap housing member 45. The lower end of the screw 86 is provided with a breaker 89 which bears upon a portion of the roll housing 35, near one end of this housing. The upper portion of the screw 86 is squared and a hand wheel 90 is mounted thereon so as to rotate with the screw. A bracket 91, secured to the member 45, provides a bearing for the screw 86 above the hub of the wheel 90. Obviously, when the hand wheel 90 is rotated it will cause the screw 86 to move up or down by reason of the threaded action between the screw and the sleeve or nut member 88. Of course, this up or down movement can occur only when there is nothing to interfere, that is to say the opposing screws must be properly positioned.

At the bottom of the housing 35, at a point directly below the screw 86, is a shoe 92 which has a horizontal upper face and inclined lower faces, as clearly shown in Fig. 14. The horizontal upper face permits the housing 35 to be moved laterally as before pointed out and it might be mentioned at this point that such lateral movement must be brought about when the screw 86 is in elevated or non-pressing position. Cooperating with the inclined or wedge faces of the shoe 92 are blocks 93, which are provided with laterally extending threaded openings into which or through which extends the screw 87. This screw is provided with opposing threads, that is to say, one-half of the threaded portion is provided with right hand threads and the other half of the threaded portion is provided with left hand threads. The blocks 93, therefore, move together when the screw 87 is rotated in one direction and they move apart when the screw is rotated in the opposite direction. The screw 87 is provided with two bearings 94 and 95 which are firmly secured to the base member 42 of the housing. The outer end of the screw 87 passes through the housing member 43 and has a hand wheel 96 secured to its outer end in position to be easily rotated by an attendant. Obviously, when the blocks 93 are moved together they will act upon the shoe 92 to raise the latter and when they are moved apart they will allow the shoe to descend and with it carry the housing 35.

Upon inspection of Fig. 14, it will be seen that the blocks 93 at the left are apart and the blocks 93 at the right are close together. It will also be noted that the screw 86 at the left is in its lowermost position, while the screw 86 at the right is in its uppermost position. When the parts are in these positions, then the axis of the two rolls R¹ and R² lie in the same horizontal plane. This arrangement is such that the left hand roll R¹ is adjusted upwardly from that plane and the right hand roll R² is adjusted downwardly from that plane. Obviously, these rolls might be otherwise adjusted and with the mechanisms modified slightly, the planes to which they

be brought when in their limiting positions might be other than the horizontal plane mentioned.

It will be noted also that the screw 87 at the right extends through an opening in the upper right housing member 44 and is provided with a hand wheel 96. In this respect there is a reversal of the parts over that shown for the parts at the left.

It is clear that many suitable arrangements might be made for feeding blanks A into the pass of the mill C. However, I have shown in the present instance (Fig. 19) guides or skids 99 over which the shell blanks may be passed into the pass in the mill. Any suitable way may be employed for pressing the blank forward into the 15 pass. In addition to the skids 99, I have also shown other skids or guides 100 and 101 which lead from the furnace B to the skids 99. The arrows indicate the direction of travel of the blanks. Of course, these blanks are only forwarded after being properly heated in the furnace B. Such heating will ordinarily be that which is required by rolling practice. From the outlet of the mill, the shell will pass down over the pivoted shelf 61, as before pointed out, and 20 will pass therefrom onto other skids 102. From these, the finished shell blanks D may be conveyed to a place of cooling and then machined or otherwise put in shape for loading as before pointed out.

The mill rolls may be driven in any desired way. In the present instance, however, the roll R² is driven through the medium of a spindle 103 and suitable universal couplings 104 and 105. Power is derived from a suitable source applied to the shaft 106 of the reducing gear mechanism 107. This constitutes the drive mechanism, E, previously referred to. Similarly the roll R¹ is driven through the agency of a spindle 108, couplings 109 and 110 and the reducing gear mechanism 111, power being applied to the shaft 112. This latter constitutes the drive mechanism F, previously referred to.

Obviously, in carrying out the present information, quite different equipment might be employed than that shown and described, but what is dis-

closed is at least typical. The cross rolls are of importance since they serve to perform the necessary functions by simple and effective mechanism, although, of course, other reducing and twisting means might be employed if desired.

I claim:

1. The process of making ordnance shell, which process includes heating a bell-shaped blank to working temperature and thereafter while hot simultaneously reducing and twisting the same, the reducing being performed to lessen the diameter of the blank and the twisting varying in extent from a maximum near the shell base to a minimum toward the ogive.

2. The process of making ordnance shell out of a conical blank of predetermined design, which process includes heating the conical blank to a temperature suited for rolling, and then simultaneously rolling and twisting the blank while hot, the rolling and twisting reducing the diameter of the blank and progressively shifting the material from a minimum twist at the ogive of the shell to a maximum at its base.

3. The process of making ordnance shell out of a conical blank of predetermined design, which process includes heating the conical blank to a temperature suitable for rolling, then while hot, progressively reducing the same in diameter and simultaneously with said progressive reduction, twisting the blank to give the ogive of the blank a vectorially greater rotation than the base, thereby forming a cylindrical shell wherein the base of the shell has received a greater amount of hot working both compressively and rotatively at the base of the shell than at the ogive.

4. In the making of ordnance shell, the process steps of heating a hollow conical blank to working temperature and by a rolling operation reducing the external diameter of the blank, and simultaneously therewith twisting the same while hot so as to maintain a zero twist at the ogive and to give a maximum twist at the base equal to at least one circumference vectorially considered.

WILLIAM C. CORYELL.

CERTIFICATE OF CORRECTION.

Patent No. 2,292,928.

August 11, 1942.

WILLIAM C. CORYKLL.

It is hereby certified that error appears in the printed specification of the above numbered patent requiring correction as follows: Page 2, second column, line 42, for "same" read --one--; page 4, first column, line 75, for the word "simplicity" read --similarity--; and that the said Letters Patent should be read with this correction therein that the same may conform to the record of the case in the Patent Office.

Signed and sealed this 20th day of October, A. D. 1942.

Henry Van Arsdale,
